(57) **CLAIM**

The ornamental design for a connector device for a tent, as shown and described.

DESCRIPTION

FIG. 1 is a front view of an embodiment of the connector device for a tent according to the present design;

FIG. 2 is a back view of the connector device for a tent of FIG. 1;

FIG. 3 is a top view of the connector device for a tent of FIG. 1;

FIG. 4 is a bottom view of the connector device for a tent of Figure1;

FIG. 5 is a right view of the connector device for a tent of FIG. 1;

FIG. 6 is a left view of the connector device for a tent of FIG. 1; and,

FIG. 7 is a perspective view of the connector device for a tent of FIG. 1.
